APPARATUS FOR TRAFFIC CONTROL

Robert H. Worrall, Washington, D. C.

Application January 30, 1933, Serial No. 654,201

1 Claim. (Cl. 177—337)

(Granted under the act of March 3, 1883, as amended April 30, 1928; 370 O. G. 757)

This application is a continuation in part of my application Serial No. 551,187 filed July 16, 1931.

This invention relates to improvements in a method of and apparatus for traffic control in which the operation of the traffic lights is affected by the frequency of interruption, by passing vehicles, of a beam of light which is acting upon a light sensitive cell.

10 An object of this invention is to provide a method of traffic control in which, at a street intersection, preference is automatically and proportionately given to the street which has the greatest traffic.

15 Another object of this invention is to provide apparatus for traffic control in which, at a street intersection, preference is automatically and proportionately given to the street which has the greatest traffic.

20 Present day traffic control consists of lights at a street intersection which allow traffic to flow for a given length of time along one street and then for a given length of time along the other street.

25 In case there is no traffic on one street, any traffic there may be on the other street is forced to wait until the signal favors them. So, any fixed adjustment of the timing of the lights must necessarily be decided upon by a comparison of the average traffic on the two streets. To show a favorable light to a street with no traffic on it when there is a large amount of traffic on its intersecting street creates a very unsatisfactory condition of traffic congestion. What is needed

30 is a traffic control system that will automatically respond to the fluctuations in traffic on the intersecting streets and proportionately give preference to the street having the greater traffic. This is accomplished by the following described circuit.

35 When traffic is moving on one street of the intersection, the corresponding circuit has control and allows traffic to flow as long as there is no gap in the stream of cars greater than a given time interval, say five seconds. Should such a

40 gap occur, the signal lights will change, giving the other street the right of way. In case traffic should be so heavy on one street that no five-second gap occurs, the control remains with the traffic until a time limit relay functions. This

45 time relay may be set for any desired time, say five minutes, whence the lights will change and the control will be given to the circuit associated with the other street. This type of control keeps traffic moving and reduces accumulative congestion which otherwise would occur.

This system is designed to control traffic at an intersection of two routes, for example, a north-south route and an east-west route. Assume that there is no traffic on the east-west route but that control is still with the circuits associated with this route. A machine approaches this intersection on the north-south route and upon passing a point on the road before arriving at the intersection, a relay is tripped through the medium of a light sensitive cell, or other methods described later on. As the control is in the east-west route for a given length of time, say five seconds, nothing happens until that period has elapsed. Then the control shifts to the north-south route which gets a green light. If a car passes along the north-south route every four seconds for two minutes the control will stay with the north-south route for that time and upon a five-second gap at the expiration of that time it will shift to the east-west route again which will get a green light while the north-south route will have a red light. As long as cars come along every four seconds or less, the control will remain with that route for a predetermined length of time when it will shift automatically to the other route. If no traffic comes along either route the lights will change every five seconds. If, in both streets, the beams of light acting upon the light sensitive cells are interrupted and remain blocked, the route which last had control would keep control until the time limit relay functions and when the traffic moved the control circuits would function as before. Should one traffic light burn out, the whole system would shut off.

45 Further objects of my invention will appear in the subsequent detailed description.

I practise my method and attain these objects by the apparatus illustrated in the accompanying drawings, in which:

50 Fig. 1 is a diagrammatic sketch showing the complete circuits as applied to two through streets;

Fig. 2 is a diagrammatic sketch of the traffic control circuits;

55 Fig. 3 is a diagrammatic sketch showing a system of power supply and the method of cutting out the entire system in case any light burns out.

The traffic control system, Fig. 2, is composed 50 of the following circuits:

A source of steady light and current supply for same 10 and duplicate circuit 11;

60 A light sensitive cell 12 in series with a relay 55

52 and battery 16 and duplicate circuits 13, 53 and 17;

A control circuit comprising battery 18, wire 54, contact 55, armature 14, wire 56, wire 57, armature 58, contact 59 or (contact 60 and wire 61), wire 62 and solenoid 63; and duplicate control circuit comprising battery 19, solenoid 64, wire 65, armature 15, contact 66, wire 67, contact 68 or (wire 70 and contact 69), wire 72 10 and wire 73.

A light and control shifting circuit comprising battery 22, wire 82, contact arm 74, contact arc 75, wire 76, wire 57, armature 58, contact 77, wire 78, relay 26, wire 79, relay 24, wire 80, time limit relay 30, contact arm 162, contact arc 163 15 and wire 81; and duplicate light and control shifting circuit comprising battery 23, wire 83, contact arm 84, contact arc 85, wire 86, wire 72, armature 71, contact 87, wire 88, relay 27, wire 20 89, relay 25, wire 90, time limit relay 31, contact arm 164, contact arc 165 and wire 91.

A signal light circuit comprising battery 28, wire 92, light G, wire 93, contact 94, armature 95 and wire 107, or battery 28, wire 96, light R, wire 97, contact 98, armature 95 and wire 107; and duplicate circuit comprising battery 29, wire 99, light G, wire 100, contact 101, armature 102 and wire 106, or battery 29, wire 103, light R, wire 104, contact 105, armature 102 and wire 106.

Referring to Fig. 2, the circuit that is first turned on will take control. Assuming this to be the upper one, the beam of light from source 10 strikes light sensitive cell 12, causing armature 14 to make contact with 55 closing the circuit from battery 18, wire 54, contact 55, wire 56, wire 57, armature 58, contact 59, wire 62 and solenoid 63 which through its armature 20 moves contact arms 74 slowly from right to left toward the off position, the motion of arm 74 being retarded by dash pot 123. While contact arm 74 is on contact arc 15, current flows through battery 22, wire 82, contact arm 74, contact arc 75, wire 76, wire 57, armature 58, contact 59, wire 78, relay 26, wire 79, relay 24, wire 80, time limit relay 30, contact arm 162, contact arc 163 and wire 81. Relay 26 being energized holds armature 71 against contact 68 and relay 24, being energized, holds armature 95 against contact 94, causing the upper green light to be lighted. The corresponding circuit through battery 23, wire 83, contact arm 84, contact arc 85, wire 86, wire 72, armature 71, contact 87, wire 88, relay 27, wire 89, relay 25, wire 90, time limit relay 31, contact arm 164, contact arc 165 and wire 91 is interrupted at contact 87 which is open and may also be interrupted by contact arm 84 being in the off position. There being no current through relay 27, the armature 58 by its spring is held 50 against contacts 59 and 77 and there being no current through relay 25, armature 102 makes contact with 105, causing the lower red light to be lighted. During this condition, if the light from source 11 is not interrupted, arm 84 will be held in the off position, the solenoid 64 being energized through wire 65, armature 15, contact 66, wire 67, contact 68 (relay 26 being energized), wire 73 and battery 19; and if light source 11 is interrupted, the arm 84 by its spring will be 60 moved to the on position. But this will have no effect on circuit 23, 83, 84, 85, 86, 71, 87, 88, 21, 89, 25, 90, 31, 164, 165 and 91 which remains open-circuited during this condition at contact 87. And when the circuit 22, 82, 74, 75, 76, 57, 78, 58, 77, 78, 26, 79, 24, 80, 30, 162, 163 and 81 is

broken by either contact arm 74 reaching the off position or the functioning of time limit relay 30, relay 26 is de-energized and its armature 71 by its spring is moved to the right, closing contacts 87 and 69. When armature 71 leaves contact 68, it opens for an instant circuit 19, 64, 65, 15, 66, 67, 68 (open), 71, 72, 73, de-energizing solenoid 64 and, regardless of the position of arm 84, insuring its setting by its spring to the beginning of its "on" position. When armature 71 contacts with contact 87, the circuit 23, 83, 84, 85, 86, 71, 87, 88, 27, 89, 25, 90, 31, 164, 165 and 91 is energized, relay 27 moving armature 58 to the left against contact 60 and relay 25 moving armature 102 against contact 101, 15 causing the lower green light to be lighted and the lower red light to be extinguished by interrupting its circuit 29, 102, 105, 104, R, 103 at contact 105. When armature 58 opened contact 71, it insured the interruption of circuit 22, 82, 20 74, 75, 76, 57, 58, 77 (open), 78, 26, 79, 24, 80, 30, 162, 163 and 81 regardless of the position of arm 74. This leaves relay 24 de-energized, opening contact 94 and closing contact 98 thus extinguishing the upper green light and causing the 25 upper red light to be lighted.

While the upper circuit has control it will maintain such control for five seconds and if at the end of that interval no car has interrupted the beam of light from 10, the arm 74 reaches 30 the "off" position, breaks the upper circuit allowing the armature 71 to open contact 68 and to close contacts 69 and 87 and the arm 84 to move to the "on" position closing the lower circuit, and the contact 98 of relay 24 to close 35 lighting the upper red instead of the upper green light. As soon as current flows through the lower circuit, it closes the contact 101 of relay 25, lighting the lower green instead of the lower red light, and closes the front contact 60 of relay 27. Thus, assuming no cause of interruption between light sources 10 and 11 and their respective cells 12 and 13, which corresponds to a condition of no traffic, the control will pass from one circuit to the other every 5 seconds accompanied with a corresponding change in lights. However, if, before the five-second interval has expired, a car interrupts the beam of light from 10, armature 14 will open contact 55, breaking the current in solenoid 63, allowing arm 74 to move to the beginning of the "on" position, and begin another five-second period. In this manner the upper circuit can maintain control as long as it has a steady stream of traffic, but will shift to the lower circuit if a five-second period 50 lapses without an interruption of the beam from 10. When the lower circuit has control and traffic on that route continues, it likewise will 55 maintain control.

If continuous traffic prevails on the route for 60 the upper circuit for any predetermined period, such as five minutes, then time limit relay 30 will operate giving control to the lower circuit. The same is true of the lower circuit where, at the expiration of five minutes continues traffic, 65 time limit relay 31 will give control to the upper circuit.

The operation of time limit relay 30 is as follows: When it is de-energized, the spring moves contact arm 162 to an upper position on contact 70 arc 163. When the relay is energized, it pulls armature 166 downward, moving contact arm 162 against the action of dash pot 167 which creates a five minute delay before it releases. Upon the release of dash pot 167, the pull on armature 166 75

being considerably greater than that of the opposing spring, the contact arm 162 because of such sudden release will begin to move rapidly and when it breaks contact with contact arc 163 and time relay 30 is de-energized, the inertia of contact arm 162 will carry it on a space sufficient to insure that the contact with contact arc 163 is broken. Such downward movement of the contact arm is not resisted by dash pot 168 but it does 10 resist the return upward movement under the influence of the spring. The contact must remain open a fraction of a second to allow sufficient time for armature 11 to move from left to right to throw control to the lower circuit. The dash pot 168 15 creates a three-second delay in the return of contact arm 162 to its initial position. This delay must be less than five seconds to insure the resetting of the contact arm before the earliest period at which control could be returned to the 20 upper circuit. During its upward movement the contact arm is not opposed by dash pot 167.

The operation of time limit relay 31 is similar to that of relay 30.

For the circuit shown in Fig. 1, the fundamental operation is the same as that described for Fig. 2.

The control circuits associated with the north-south street are: A control circuit comprising battery 46, wire 108, wire 109, contact 110, armature 111, wire 112, armature 113, contact 114, wire 115, solenoid 116, wire 117, contact 118 (or contact 124), armature 119 and wire 120; and a light and control shifting circuit comprising battery 46, wires 108 and 121, contact arc 122, contact arm 125, wire 126, contact arc 169, contact arm 170, time limit relay 48, wire 127, relay 42, wire 128, relay 44, wire 129, contact 130, armature 119 and wire 120.

The control circuits associated with the east-west street are: A control circuit comprising battery 47, wire 131, armature 144, contact 132 (or contact 133), wire 134, solenoid 135, wire 136, contact 137, armature 138, wire 139, armature 140, contact 141, wire 142 and wire 143; and a light and control shifting circuit comprising battery 47, wire 131, armature 144, contact 145, wire 146, relay 45, wire 147, relay 43, wire 148, time limit relay 49, contact arm 171, contact arc 172, wire 149, contact arm 150, contact arc 151, wire 152 and wire 143.

The lighting circuits are: A circuit comprising battery 161, wire 153, armature 154, contact 155, wire 156, lights R' and G' and wire 157; and another circuit comprising battery 161, armature 158, contact 159, wire 160, lights R and G and wire 157.

In Fig. 1, sources of light 32, 33, 34 and 35 would actually be placed at the center of their respective streets, and light sensitive cells with their relay circuits 36, 37, 38 and 39 would be placed respectively on that side of the street which is right for traffic approaching the intersection, so that only when a car approaches the intersection does it interrupt a beam of light, but in passing 65 on across or turning right or left it does not interrupt the other beams of light.

When east-west has control, an interruption of either beam 32-36 or beam 33-37 will reset the arm 150 to the "on" position. The contacts 145 and 133 are closed, the contact 124 is closed, and 70 155 is open. The contact 159 is closed, lighting lights G and R.

When the arm 150 reaches the "off" position or time limit relay 49 functions, the control is shifted to the north-south routes. This sets the arm 125

to the "on" position if not already there, allows contacts 130 and 118 to close, opens 159 and closes 132. It also closes the contact 155 of relay 43 lighting lights G' and R'. The control remains with the north-south route until 125 reaches the "off" position or time limit relay 48 functions. Both time limit relays 48 and 49 function similarly to time limit relay 30 described above. The control shifts back and forth automatically and proportionately to the amount of 10 traffic on the intersecting streets.

In Figs. 1 and 2, for simplicity, batteries have been shown as sources of energy. Actually, the circuits would be energized by the local lighting system. When so energized, Fig. 3 shows a method of cutting out all the lights in case one is burned out. All lights are in parallel and each light is fed through a no-voltage release 50, whose contacts are all in series with the primary of the transformer which feeds the entire system. If 20 one light burns out and its no-voltage release drops, the primary of the transformer is opened, shutting off the entire system. After the light is replaced, the switch 51 is momentarily closed, lighting all lights and closing the no-voltage releases which restores the circuit to its normal state.

Referring to Fig. 1, the circuit 46, 108, 121, 122, 125, 126, 169, 170, 48, 127, 42, 128, 44, 129, 130, 119, 120 being closed, contacts 159, 145 and 133 30 are open and contact 155 is closed, causing the lights R' and G' to be lighted. As the above mentioned circuit is interrupted by time limit relay 48 or arm 125 reaching the off position, the armatures 158 and 144 are moved by their respective springs. In the meantime, armature 154 due to its spring still makes contact with 155 and this contact will not be broken until armature 144 makes contact with 145 energizing circuit 47, 131, 144, 145, 146, 45, 147, 43, 148, 49, 171, 172, 149, 40 150, 151, 152 and 143. But by that time armature 158 will have made contact with 159, causing the lights R and G to be lighted. So that for a very short period all signal lights will be lighted and serve as a warning of a change. The contacts 45 159 being closed before contact 155 is opened and vice versa, contact 155 being closed before 159 is opened, it is clear that at no time, due to the operation of the signaling system, have the no-voltage releases 50 an opportunity to function, but 50 as soon as one light burns out, these no-voltage releases will function to open the circuits to all the signal lights. This is advantageous to prevent accidents. Suppose a car on each street is approaching the intersection and the one which according to the traffic rules would have a right-of-way is supposed to have a red light but the red light is burned out, the other car having a favorable green light continues into the intersection, and the one thinking the traffic laws control, not 60 knowing of the signal lights, also continues into the intersection and a collision results. It is evident that it would be dangerous to operate such a traffic system without some such cutting-off device.

There are other means for operating the relays by passing cars, such as through the medium of a vacuum tube bridge circuit, where a change in capacity would cause a current to flow operating the relay; or an oscillating vacuum tube circuit 70 where a change in capacity would cause the circuit to oscillate and current to flow operating the relay.

While in the foregoing there has been illustrated and described such combination and ar- 75

angement of elements as constitute the preferred embodiment of my invention, it is nevertheless desired to emphasize the fact that interpretation of the invention should be conclusive only when made in the light of the subjoined claim.

The herein described invention may be manufactured and used by or for the Government of the United States of America for governmental purposes without the payment of any royalties thereon.

I claim:

In a traffic control system for intersecting streets, a "go" signal and a "stop" signal for each street, a switch arm individual to each street, a contact arc with an insulating segment at one end over which said switch arm is adapted to pass, spring means for moving said arm in one direction, electromagnet means for moving said arm in the other direction toward the insulating segment, means associated with said arm opposing said electromagnetic means for controlling the passing of said arm over said arc

with respect to a predetermined interval of time, means comprising traffic actuated devices for de-energizing said electromagnetic means permitting said spring means to move said switch arm, a signal and control shifting circuit associated with each street comprising a signal shifting relay, a time delay relay and an interlocking relay in series with said switch arm, contact arc and a source of potential, said interlocking relay in the said signal and control shifting circuit of one street having a front contact and a back contact each of which energizes the said switch arm electromagnetic means associated with the other street and another back contact which closes the control circuit associated with the said other street, said time delay relay and said insulating segment operating to open said signal and control shifting circuit and said interlocking relay, in moving from its front to its back contacts, operating to shift control to the other control circuit.

ROBERT H. WORRALL.
